UNITED STATES PATENT OFFICE.

ALWIN G. STEINMAYER, OF MILWAUKEE, WISCONSIN, ASSIGNOR TO LINE MATERIAL COMPANY, OF SOUTH MILWAUKEE, WISCONSIN, A CORPORATION OF WISCONSIN.

CONTACT TERMINAL.

Application filed October 12, 1925. Serial No. 62,021.

This invention has as an object the provision of an improved contact terminal member wherein a better electrical connection is obtained between the conductor and the switch terminal and one in which the length of terminal tongue may be varied to suit any condition.

It is another object of this invention to provide an improved contact terminal which by reason of its construction may be manufactured at a relatively low cost.

A further object of this invention is to provide an improved clip construction designed to exert its pressure in the contact area where it is needed and only after the blades are well in contact to thus lessen the strain on the insulators and switch parts during the opening and closing operations.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, I have illustrated one complete example of the physical embodiment of my invention constructed according to the best mode I have so far devised for the practical application of the principles thereof and in which:

Figure 1 is a side view of a switch equipped with contact terminals embodying my invention, a part of the movable switch member being broken away and in section, and

Figure 2 is a view, partly in section and partly in elevation, taken through Figure 1 on the plane of the line 2—2.

Referring now more particularly to the accompanying drawing, in which one embodiment of my invention is illustrated, the numeral 5 designates a supporting base or panel upon which two insulators 6 and 7 are mounted in spaced relation by fastening bolts or other members 8. The outer ends of the insulators 6 and 7 have my improved contact terminals 9 and 10, respectively, mounted thereon by attaching bolts 11. The blades 12 of a movable switch member 13 are pivotally connected with the vertical portion 14 of the terminal 9 in electrical en-

gagement by a pivot pin and friction washers 15, the blades being disposed on opposite sides of the vertical portion and thus maintained in proper spaced relation. The free ends of the movable switch member blades 60 are connected and held in spaced relation by an operating eye member 16 and the member is engageable over the vertical part 17 of the terminal 10 between spring clips 18 fixed thereto, as at 19.

The terminal members 9 and 10 are preferably cut from T-shaped copper rails to the desired width and the vertical portion 14 of the rail from which the terminal 9 is cut is preferably of the same thickness throughout 70 equal to the distance it is desired to space the blades 12 and the vertical portion of the rail from which the terminal 10 is cut is preferably of increased thickness at its base portion 20 with its outer end portion 17 of 75 a thickness equal to that of the vertical portion of the terminal 9 to form shoulders 21 adapted to be engaged by the inner edge portions of the blades 12 when closed.

The outer faces of the transverse portion 22 of the rails from which the terminals are cut are provided with central, longitudinal slots or recesses 23 in which are secured terminal tongues 24 which provide means for electrically connecting the conductor sockets 25. The tongues 24 are cut from strip copper of a thickness and width adapted to fit snugly within the slots 23 to be held therin against the top of the insulator by the bolts 11. The terminal tongues 24 are of lengths 90 best fitted for the use to which the terminal members are being put and the conductor sockets 25 are bolted or otherwise secured thereto, as at 26. This arrangement places the terminal tongues in better electrical contact with the terminal members proper and also, as mentioned above, affords terminal tongues of any desired lengths.

As best shown in Figure 2, the clip members 18 are preferably formed of strip material and have their medial portions curved outwardly to approximately semi-circular form, one end portion of the clip member forming means for attaching the clip to the terminal portion 20 and the other end portion being flared outwardly to form a tapered guide-way for the switch blade. In this manner the pieces 18 insure a good spring pressure on the blades which is exerted only after the blades are well in con- 110

tact, thus lessening strain on the insulators and switch parts during the opening and closing operations.

From the foregoing description taken in connection with the accompanying drawing it will be readily obvious to those skilled in the art to which an invention of this character appertains that I provide an improved terminal member which may be readily formed from stock material which will be very efficient in operation and one in which the electrical connection between the terminal tongue and the terminal proper is very efficient and practical.

15 I claim:

1. In a device of the character described, a support, a contact member, means securing the contact member to the support, there being a slot in the contact member on its face engaging the support, and a terminal tongue of the desired length secured in said slot in electrical connection with the contact member and held therein by the means securing the contact member to the support.

25 2. A device of the character described, comprising a contact member cut from a length of T-shaped material having the outer face of its transverse portion provided with a central, longitudinal slot, and a terminal 30 tongue cut from a length of strip material and of a thickness and width equal to the depth and width of the slot to provide a good electrical engagement in said slot, said terminal tongue projecting from the contact member to provide means for electrically connecting a conductor with the contact member.

35 3. A device of the character described,

comprising a contact member cut from a length of T-shaped material having the outer face of its transverse portion provided with a central, longitudinal slot, a terminal tongue cut from a length of strip material and of a thickness and width equal to the depth and width of the slot to provide a good electrical engagement in said slot said terminal tongue projecting from the contact member to provide means for connecting a conductor with the contact member, and means on the vertical portion of the contact member to provide for the electrical engagement therewith of a switch member.

4. In a device of the character described, a support, a substantially T-shaped contact member having a slot in the under face of its transverse portion, a terminal tongue snugly fitted in the slot to have a good electrical contact with the contact member, and means passed through the transverse portion of the T-shaped contact member for securing the same to the support.

5. In a device of the class described, a contact member cut from a length of T-shaped material and having a slot formed in the under face of its transverse portion, a terminal tongue cut to desired length from strip material and snugly fitted in the slot and in good electrical engagement with the contact member, and a pair of complementary clip members mounted one on each side of the vertical portion of the T-shaped member to provide means for engaging a movable switch member with the contact member.

In testimony whereof I affix my signature.
ALWIN G. STEINMAYER.
